RAILWAY TRAFFIC CONTROLLING
APPARATUSJames J. Vanhorn, Swissvale, Pa., assignor to The
Union Switch & Signal Company, Swissvale,
Pa., a corporation of Pennsylvania

Application October 28, 1939, Serial No. 301,818

13 Claims. (Cl. 246—26)

My invention relates to railway traffic controlling apparatus, and particularly to the type known as traffic locking apparatus, which requires joint action by persons at two different control stations for manually controlling traffic movements in both directions over a stretch of railway track.

More specifically, my invention relates to traffic locking apparatus in which a manually operable traffic control device, such for example as a lever, free at all times to be moved between normal and reverse control positions, is provided at one of the two control stations, and in which there is provided, at the other of the two control stations, a second manually operable traffic control device, such for example as a lever, having a normal and a reverse control position and also a normal and a reverse lock position between the normal and reverse control positions, and equipped with an electric lock which when de-energized prevents movement of the second lever from either of its control positions beyond the corresponding lock position, but which when energized releases the second lever for such movement.

One feature of my invention is the provision of novel and improved means for requiring proper joint action by persons at the two control stations, when operating these two traffic control devices for controlling traffic movements in each direction over the stretch of railway track. Another feature of my invention is the provision of novel and improved means for signaling from each of the two operators to the other.

I shall describe one form of apparatus embodying my invention, and shall then point out the novel features thereof in claims.

The accompanying drawings, Figs. 1a and 1b, when placed end to end, with Fig. 1a on the left, constitute a diagrammatic view showing one form of apparatus embodying my invention.

Referring to the drawings, the reference characters 8 and 8a designate the track rails of a stretch of single track railway over which traffic movements may be made in either direction. Adjacent the left-hand end of this stretch of single track as shown in Fig. 1a of the drawings, which I shall assume is the west end, is a switch 2W leading to an auxiliary track X. Adjacent the opposite or east end of the stretch of track, is a second switch 5W leading to a second auxiliary track Z.

Rails 8 and 8a are divided by insulated joints 10 to form a switch section 2T in which switch 2W is located, and to form a second switch section 5T

in which switch 5W is located. Between sections 2T and 5T, rails 8 and 8a are further divided into other sections. As shown in Fig. 1a, rails 8 and 8a are divided into only two sections 3T and 6T between sections 2T and 5T, but may be divided into more than two sections if desired. Each track section is provided with a track circuit including a suitable source of current, such as a track battery 12 connected across the rails adjacent one end of the section, and a track relay, designated by the reference character R preceded by the reference character for the associated section, connected across the rails adjacent the opposite end of the section.

Eastbound traffic movements over the stretch 15 of railway track are governed by signals 3RA and 3RB when switch 2W is in its normal position as shown in Fig. 1a, and are governed by signal 3RC when switch 2W is reversed. Westbound traffic movements over the stretch of railway track are governed by signal 6LC when switch 5W is in its normal position, and by signals 6LA and 6LB when switch 5W is reversed. Other signals may also be located between sections 2T and 5T for governing traffic movements 20 in both directions. The signals may be of any suitable type, such for example as position light signals.

Signals 3 are controlled by a manually operable lever or other control device 3V located at a given control station such for example as an interlocking tower adjacent switch 2W, and having a normal position n, a reverse position f to the left for controlling signal 3L, and a reverse position r to the right for controlling signals 3R.

A manually operable traffic control lever 1V, located in the same control station, is mechanically interlocked with lever 3V as indicated by the dash line 14, so that lever 1V must be in its normal position N before lever 3V can be moved to its reverse position r, and lever 1V must remain in its N position while lever 3V remains in its r position. Lever 1V has also a reverse position R, and normal and reverse lock positions B and D, respectively.

Lever 1V is provided with a lock comprising a locking segment 15, which is mechanically operated by lever 1V, and a lock magnet 1M which controls a locking dog 16. When magnet 1M is deenergized, locking dog 16 engages a projection 50 20 on segment 15 if lever 1V is moved to its lock position B or D, thus preventing movement of lever 1V from either of its extreme positions to the other until magnet 1M again becomes energized.

- Lever $1V$ operates a plurality of contacts each of which is represented by a circle in which is placed one or two reference characters corresponding to the positions of lever $1V$ at which the corresponding contact is closed. Contact 78 , for example, is closed only when lever $1V$ is in its R position, and contact 53 is closed while lever $1V$ is in the N or the D position or in any other position between these two positions.
- 10 Lever $3V$ operates a contact 91 which is represented similarly to the contacts, just described, which are operated by lever $1V$.

An auxiliary manually operable circuit controller, here shown as a push button $1PB$ which may be spring biased to the normal position in which it is shown in the drawings, is associated with traffic lever $1V$.

Located at the second control station, is a second manually operable traffic control device shown as a lever $4V$ having a normal position n and a reverse position r between which lever $4V$ is movable at all times. Associated with lever $4V$ is a second auxiliary manually operable circuit controller $4PB$ shown as a push button spring biased to the normal position. Lever $4V$ and push button $4PB$ may be used to control portions of the apparatus shown in the drawings through a direct wire system in which the contacts of this lever and push button would be connected directly with the portions of the apparatus controlled, or they may be used to control the portions of the apparatus through a code system in which a single two-wire line circuit is employed.

35 As shown in the drawings, lever $4V$ and push button circuit controller $4PB$ are arranged with other control and indication equipment in the second control station, which may for example be a dispatcher's office, for controlling and being controlled by, respectively, other apparatus adjacent switch $5W$, through code control equipment. I shall assume that this code control equipment is of the time code type shown and described in the United States application for Letters Patent 45 Serial No. 600,786, filed March 23, 1932, by L. V. Lewis for Remote control systems.

Office code equipment, in response to manual control equipment including lever $4V$ and push button $4PB$, and also a lever $6V$, transmits control code signals, over line conductors YL and ZL , to field code equipment including a delivery relay L , which in turn causes positive energy to appear at its terminals, including terminals 9 , 11 , 13 , 19 and 21 , according to the control code signal transmitted.

50 Lever $4V$ thus controls normal and reverse traffic stick relays designated by the reference characters $4NFS$ and $4RFS$, respectively, and push button circuit controller $4PB$ controls an indication stick relay $4PBM$, through contacts of delivery relay L . Also, lever $6V$ controls relays $6RHSM$ and $6LHSM$ for controlling signals $6R$ and $6L$, respectively.

The field code equipment, in response to indication energy supplied over contacts of relays adjacent switch $5W$ to terminals 3 , 4 , 5 , 6 , 7 , 17 and 18 , transmits indication code signals, over line conductors YL and ZL , to the office code equipment, which in turn causes positive energy to be supplied to control the energization of indication lamps e according to the indication code signal transmitted.

70 The contacts operated by the various relays and other control devices are identified by numbers, each such number having a distinguishing

prefix from which it is separated by a dash when the associated contact is shown apart from the relay or other device by which it is operated. The prefix for each of these contact numbers comprises the reference character for the relay or other device by which the associated contact is operated. For example, contact $4RFS-79$, shown in the circuit for relay $4TMA$ adjacent the symbol for this relay, is identified by the number 79 which is separated by a dash from the prefix $4RFS$ which is the reference character for relay $4RFS$ by which this contact is operated.

A lock relay $4TM$ is controlled by front contacts of all of the track relays for the stretch of track shown in the drawings.

An indication or lock relay $1TMA$ in the first control station controls lock magnet $1M$ and a first indication device here shown as a lamp $e1$. Energization of relay $1TMA$ is effected by the energization of relay $4PBM$ while relay $4NFS$ is energized and while auxiliary circuit controller $1PB$ is in its normal position.

When magnet $1M$ is energized, lever $1V$ can be operated from either of its extreme positions to the other for operating pole changing contacts 27 , 28 , 65 and 66 which control polarized traffic control relays DSA , DSB and DSD . Relay DSD controls normal and reverse traffic control relays $DSDWM$ and $DSDEM$, respectively.

Energization of an auxiliary traffic control relay $4TMA$ is effected by operation of the push button circuit controller $1PB$ while lever $1V$ is in its reverse position and while relay $4RFS$ is energized. A stick traffic control relay $4TMAS$ becomes energized when relay $4TMA$ becomes energized while relay $DSDEM$ is energized.

An approach locking stick relay $6LKM$ associated with signals $6L$, in addition to being controlled by contact $6LHSM-26$ as shown in Fig. 1a, may be controlled in any suitable manner, similarly, for example, to relay L in Letters Patent of the United States No. 1,956,851 granted May 1, 1934, to C. A. Brooks and J. M. Pelikan for Railway traffic controlling apparatus.

A switch locking repeater relay $5KM$ is controlled in part by approach locking relay $6LKM$, and by a second approach locking relay $6RKM$ associated with signal $6R$.

55 A second and a third indication device, for showing traffic direction control, designated by the reference characters $e2$ and $e3$, respectively, are controlled through the code equipment by relays $4NFS$ and $4RFS$, respectively, and by relays DSD and $4TMAS$. A fourth indication device or block indicator $e4$ is controlled by relay $4TM$. A normal and a reverse traffic indication device en and er , respectively, are controlled by relays $4TM$ and DSD .

Having described, in general, the arrangement and control of the apparatus shown by the accompanying drawings, I shall now describe, in detail, its operation.

As shown by the drawings, all parts are in the normal condition, that is, switches $2W$ and $5W$ are in their normal positions; all signals shown are indicating "stop"; levers $1V$, $3V$, $4V$ and $6V$, and the auxiliary circuit controllers $1PB$ and $4PB$ are in their normal or first positions; contacts 27 , 28 , 58 and 59 of lever $1V$ are closed, and contacts 65 , 66 , 78 and 81 of lever $1V$ are open; the relays $4TM$, $6LKM$, $6RKM$, DSA , DSB , DSD , $DSDWM$, $5KM$ and $4NFS$ are energized; relays $1TMA$, $4TMA$, $DSDEM$, $4TMAS$, $6LHSM$, $6RHSM$, $4RFS$, L and $4PBM$, and lock magnet $1M$ are deenergized; locking dog 16 is in en-

gament with locking segment 15; indication lights *e1*, *e3*, *e4* and *er* are extinguished; and indication lights *e2* and *en* are energized.

The circuit by which lock relay 4TM is energized passes from terminal B of a suitable source of current, not shown in the drawings, through contacts 22, 23, 24 and 25 of relays 2TR, 3TR, 6TR and 5TR, respectively, and the winding of relay 4TM to terminal C of the same source of current.

Relay 6LKM is energized by a circuit, only a portion of which is shown, including contact 6LHSM-26.

Relays DSA, DSB, and DSD are energized, in multiple, by current of normal polarity in a circuit passing from terminal B, through contact 27 of lever 1V, the windings of these relays, and contact 28 of lever 1V to terminal C. With relay DSD thus energized, relay DSDWM is energized by a circuit passing from terminal B, through contact 29 of relay DSD, contact 30 of relay DSD in the left-hand or normal position, and the winding of relay DSDWM to terminal C.

Relay 5KM is energized by a circuit, only a portion of which is shown, passing through contact 31 of relay 6RKM, contact 6LKM-32, and the winding of relay 5KM to terminal C.

Relay 4NFS is energized by a stick circuit passing from terminal B, through contact 33 of delivery relay L, terminal 21 of the field code equipment, contact 4RFS-36, contact 38 of relay 4NFS, and the winding of relay 4NFS to terminal C. A second stick circuit is also closed for this relay, passing from terminal B, through contact DSDWM-37, contact 38 of relay 4NFS, and the winding of relay 4NFS to terminal C.

The second or eastbound traffic direction indication device *e2*, is energized by a circuit controlled by current supplied from terminal B, through the back point of contact 4TMAS-39, contact DSD-40 closed in the normal position, and the front point of contact 4NFS-41 to terminal 5 of the field code equipment. Normal traffic indication device *en* is also energized by a circuit controlled by current supplied from terminal B, through the front point of contact 4TM-43, front point of contact DSD-44, and contact DSD-45 closed in the normal position to terminal 6 of the field code equipment.

With the traffic locking apparatus, including traffic control levers 1V and 4V, in the normal condition shown in the drawings, none of the signals 6L can be cleared for a westbound traffic movement by an operation of lever 6V at the second control station, but one of the signals 3R can be cleared for an eastbound traffic movement by operation of lever 3V in the first control station to the *r* position, without any manual action at the second control station.

I shall assume that the leverman at the second control station desires the direction of traffic movement to be reversed so that a train can move in the westbound direction over a stretch of track shown. He will, therefore, depress push button 4PB, thus closing contact 4PB-46 and causing relay 4PBM to be energized by a pick-up circuit passing through the front point of contact 51 of delivery relay L in the field code equipment, terminal 9 of the field code equipment, contact 4TM-52, contact 4NFS-53, and the winding of relay 4PBM to terminal C. Relay 4PBM, after thus becoming energized, is retained in the energized position by its stick circuit passing from terminal B, through contact DSD-47, contact DSD-48 closed in the normal

position, contact 4PBM-50, terminal 19 of the field code equipment, back point of contact 51 of delivery relay L, terminal 9 of the field code equipment, contact 4TM-52, contact 4NFS-53, and the winding of relay 4PBM to terminal C. 5

Relay 4PBM, upon becoming energized, completes a circuit for energizing indication relay 1TMA in the first control station, this circuit passing from terminal B, through contact 54 of approach locking relay 6LKM, contact 55 of relay 4TMA, front point of contact 4PBM-56, contact 4TM-57, front point of the contact of push button circuit controller 4PB, contact 58 of lever 1V, winding of relay 1TMS, contact 59 of lever 1V, contact 4NFS-60, contact 61 of relay 4TMA, and contact 62 of relay 6LKM to terminal C. Relay 1TMA, upon becoming energized, completes a circuit for energizing the first indication device *e1*, this circuit passing from terminal B, through contact 63 of relay 1TMA, and 20 indication device *e1* to terminal C. Relay 1TMA, upon becoming energized, also closes a circuit for energizing lock magnet 1M, passing from terminal 1B, through contact 64 of relay 1TMA, and the winding of magnet 1M to terminal C. 25

The energization of indication device *e1* informs the leverman at the first control station that the leverman at the second control station desires the traffic direction to be reversed so that a westbound train can proceed over the stretch 30 of track shown.

With lock magnet 1M energized, thereby permitting operation of lever 1V past its normal lock position B, the leverman at the first control station will reverse lever 1V, thereby causing relays 35 DSA, DSB and DSD to be energized in the reverse direction by a circuit passing from terminal B, through contact 65 of lever 1V, the windings of the relays in multiple, and contact 66 of lever 1V to terminal C. Relay DSD, upon thus becoming 40 energized, opens contact DSD-40 in the normal position, and then closes this contact in the reverse position, thereby completing a circuit path for current to pass from terminal B, through the back point of contact 4TMAS-39, contact 45 DSD-40 closed in the reverse position, and the back point of contact 4RFS-42 to terminal 11 of the field code equipment which then transmits a code signal to the office code equipment which effects deenergization of the second or eastbound 50 traffic direction indication device *e2*. Relay DSD, upon becoming energized in the reverse direction, also opens the circuit path previously traced for current for controlling energization of normal traffic indication device *en*, and completes the 55 circuit path for current for effecting energization of reverse traffic indication device *er*, which is the same as the circuit path previously traced for device *en* as far as contact DSD-44, and then passes through contact DSD-45 closed in the reverse position, to terminal 4 of the field code equipment. 60

Relay DSD, upon becoming energized in the reverse direction, also opens contact DSD-48 65 closed in its normal position, thereby breaking the stick circuit previously traced for relay 4PBM and causing this relay to become deenergized. Relay DSD, upon becoming energized in the reverse direction, opens its contact 30 in the normal position, thereby deenergizing relay DSDWM, and then closes its contact 30 in the reverse position, causing relay DSDWM to become energized by a circuit passing from terminal B, through contact 29 of relay DSD, contact 30 of relay DSD 70 75

closed in the reverse position, and the winding of relay DSDEM to terminal C.

When the second traffic direction indication device *e2* becomes deenergized, and normal traffic indication device *en* also becomes deenergized, and reverse traffic indication device *er* becomes energized, the leverman at the second control station will reverse lever 4V, thereby completing a circuit path through contact 4V-33 closed in the reverse position, for current to pass to the office code equipment which then transmits a code signal over line wires YL and ZL to effect the closing of a pick-up circuit for relay 4RFS, whereby current flows through contact 90 of delivery relay L, terminal 11 of the field code equipment, contact DSDEM-61, and the winding of relay 4RFS to terminal C. With relay DSDWM deenergized, the second stick circuit traced for relay 4NFS is open, and the first stick circuit described for relay 4NFS has become opened at contact 89 of delivery relay L, causing relay 4NFS to become deenergized. With relay 4NFS thus deenergized when relay 4RFS becomes energized, a stick circuit is completed for relay 4RFS, passing from terminal B, through contact 89 of delivery relay L, terminal 21 of the field code equipment, contact 4NFS-68, contact 71 of relay 4RFS, and the winding of relay 4RFS to terminal C. Also, with relay 4RFS energized, the third or westbound traffic direction indication device *e3* becomes energized in response to current passing from terminal B, through the back point of contact 4TMAS-39, contact DSD-40 in the reverse position, and the front point of contact 4RFS-42 to terminal 7 of the field code equipment.

The leverman at the second control station will now move lever 6V to its *f* position, thereby initiating a code, for energizing relay 6LHSM, by completing a path for current to pass to the office code equipment through contact 86 of lever 6V closed in the *f* position. With relay 6LHSM thus energized, relay 6LKM will become deenergized by the opening of contact 6LHSM-26, causing relay 5KM in turn to also become deenergized and thereby complete a circuit, only a portion of which is shown, for clearing one of the signals 6L, this circuit passing from terminal B, through contacts 4RFS-72 and DSDEM-73, back point of contact 74 of relay 6RHSM, contact 75 of relay 5KM, front point of contact 76 of relay 6LHSM, and thence over the rest of the circuit, not shown.

Also, with relay 6LKM deenergized, a second stick circuit is completed for relay 4RFS, passing from terminal B, through contact 6LKM-70, contact 71 of relay 4RFS, and the winding of relay 4RFS to terminal C.

If a westbound train now passes signal 6LC, causing relay 5TR to become deenergized, which in turn, at its contact 25, opens the circuit for relay 4TM, causing this relay to also become deenergized, a circuit path will be completed for current to pass from terminal B, through the back point of contact 4TM-43 to terminal 18 of the field code equipment, and the field code equipment will then transmit an indication code for effecting deenergization of reverse traffic indication device *er*. At the same time, block indicator *e4* becomes energized because of current passing from terminal B, through contact 4TM-81 to terminal 3 of the field code equipment.

With relay 4TM deenergized, a third stick circuit is completed for relay 4RFS, passing from terminal B through contact 4TM-69, contact 11

of relay 4RFS, and the winding of relay 4RFS to terminal C.

I shall next assume that the leverman at the first control station wishes the direction of traffic movement to be restored to the normal condition, after the stretch of single track becomes unoccupied, to permit an eastbound train movement. He will therefore depress push button 1PB, thus completing a circuit for energizing auxiliary traffic control relay 4TMA, this circuit 10 passing from terminal B, through contact 17 of indication relay 1TMA, contact 78 of lever 1V, back point of the contact of push button 1PB, contact 4TM-57, back point of contact 4PBM-56, contact 4RFS-79, winding of relay 15 4TMA, contact 4RFS-80, contact 81 of lever 1V, and contact 82 of relay 1TMA to terminal C.

With relay 4TMA thus energized while relay DSDEM is still energized, a pick-up circuit is completed for energizing stick traffic control relay 4TMAS, this circuit passing from terminal B, through contact 83 of relay DSDEM, contact 4TMA-84, and the winding of relay 4TMAS to terminal C. Relay 4TMAS, upon becoming energized, completes a stick circuit including its 25 contact 85 instead of contact 4TMA-84 in the pick-up circuit just traced.

With relay 4TMAS thus energized, a circuit path is completed for current to flow for effecting deenergization of the third or westbound 30 traffic direction indication device *e3*, this circuit path passing from terminal B, through the front point of contact 4TMAS-39, and terminal 17 of the field code equipment.

After push button 1PB is returned, either manually or by some biasing means, to its normal position, the leverman at the first control station will move lever 1V from its reverse position R to its reverse lock position D, at which dog 16 will engage projection 20 on segment 15 and 40 interrupt further movement of lever 1V.

When the westbound traffic direction indication device *e3* becomes deenergized, the leverman at the second control station will return lever 4V to the normal position, thereby causing current to 45 pass through contact 4V-33 closed in the normal position, to the office code equipment, which then transmits a control code signal to the field code equipment for effecting energization of relay 4NFS by its pick-up circuit passing through contact 88 of delivery relay L, terminal 13 of the field code equipment, contact 4TMAS-35, and the winding of relay 4NFS to terminal C.

The leverman at the second control station will also now return lever 6V to its normal position, 55 thereby effecting deenergization of relay 6LHSM. Relays 6LKM and 5KM will then become energized.

With relays 4NFS again energized, a second pick-up circuit will be closed for energizing relay 4PBM, this circuit passing from terminal B, through contact DSD-41, contact DSD-48 closed in the reverse position, contact 4TMAS-49, contact 4NFS-53, and the winding of relay 4PBM to terminal C. In this way, relay 4PBM becomes energized without operation of push button 4PB, thereby again completing the circuit previously traced for energization of relay 1TMA.

Relay 1TMA, upon becoming energized, again completes the circuit previously traced for energizing the first indication device *e1* which again informs the leverman at the first control station that lever 1V is now free to be moved back to the normal position. The leverman at the first control station will therefore return lever 1V from 75

the D to the N position, thereby completing the normal control circuit previously traced for relays DSA, DSB and DSD.

- Contact DSDWM—34 is used in multiple with contact 4TMAS—35 in the pick-up circuit for relay 4NFS so that if both relays 4NFS and 4RFS should become deenergized at the same time, means would be available for reenergizing one of them.
- 10 The second stick circuit for relay 4NFS, which includes contact DSDWM—37, is for the purpose of preventing a change in the condition of relay 4NFS until the leverman at the first control station reverses traffic control lever IV.
- 15 The two stick circuits for relay 4RFS including contacts 4TM—69 and 6LKM—70, respectively, are for the purpose of retaining relay 4RFS in the energized condition if the leverman at the second control station should inadvertently send 20 a code to restore the normal direction of traffic while one of the signals 6L is clear or the stretch of track is occupied between signals 6L and 3R.
- From the foregoing description and the accompanying drawings, it follows that, in apparatus embodying my invention, I have provided traffic locking apparatus with novel and improved indication means for signaling between two control stations, and with novel and improved means requiring joint action by levermen in the two 30 control stations for changing the direction of traffic movements over a given stretch of railway track, while employing at one of the control stations a traffic control lever which is at times locked against operation from either of two control positions to the other, and using at the second control station a traffic control device which can be manually operated at all times between its two control positions.
- Although I have herein shown and described 40 only one form of apparatus embodying my invention, it is understood that various changes and modifications may be made therein within the scope of the appended claims without departing from the spirit and scope of my invention.
- 45 Having thus described my invention, what I claim is:
1. In combination, a stretch of railway track, a manually movable traffic control lever associated with a first end of said stretch having a normal and a reverse extreme position and also having a normal and a reverse lock position between said extreme positions, a lock for said lever which when energized releases said lever for movement between said extreme positions but which when 50 deenergized while said lever is in said normal or said reverse extreme position locks said lever against movement past said normal and reverse lock positions respectively, a first auxiliary circuit controller having a first and a second control position, a second manually operable traffic control device having a normal and a reverse position associated with the opposite end of said stretch, an auxiliary traffic control relay, a second auxiliary circuit controller biased toward a 55 first position but manually operable to a second position, a pair of conductors, a circuit including said pair of conductors controlled by said first auxiliary circuit controller in its first position and by said second auxiliary circuit controller 60 in its second position and also by said traffic control lever in its normal lock position for effecting energization of said lock, a second circuit including said pair of conductors controlled by said traffic control lever in the reverse position and by 65 said first auxiliary circuit controller in its second position and also by operation of said second traffic control device to its reverse position for energizing said auxiliary traffic control relay, means controlled by said traffic control lever in the reverse lock position and by said second traffic control device in the normal position and also by said auxiliary traffic control relay in the energized condition for also closing said first circuit for effecting energization of said lock, means controlled by said traffic control lever in the normal 10 position for controlling traffic movements in a first direction over said stretch, and means controlled by said traffic control lever and by said second traffic control device both in the reverse positions for directing traffic movements in the 15 opposite direction over said stretch.
2. In combination, a stretch of railway track, a manually movable traffic control lever associated with a first end of said stretch having a normal and a reverse position, a first manually operable auxiliary circuit controller having a first and a second control position, a first indication device, a second manually controllable traffic control device having a normal and a reverse position associated with the opposite end of said stretch, 20 a second manually operable auxiliary circuit controller, an indication stick relay, a pick-up circuit for said indication stick relay controlled by said second auxiliary circuit controller in a manually operated position, a stick circuit for said indication stick relay controlled by said traffic control lever and by said second traffic control device both in their normal positions, an auxiliary traffic control relay, a second indication device, a circuit controlled by a back contact of said auxiliary traffic control relay and by a front contact of said indication stick relay and also by said first auxiliary circuit controller in its first 25 position for energizing said first indication device, a circuit controlled by said traffic control lever in its reverse position and by said first auxiliary circuit controller in its second position and also by a back contact of said indication stick relay and by said second traffic control device in its reverse position for energizing said auxiliary traffic control relay, means controlled by said traffic control lever and by said second traffic control device both in their reverse positions for energizing said second indication device, and means controlled by a front contact of said auxiliary traffic control relay for deenergizing said second indication device.
3. In combination, a stretch of railway track, a manually controllable traffic lever associated with one end of said stretch having a normal 30 position for governing traffic movements in a first given direction over said stretch and also having a reverse position, a lock for said lever which when energized releases said lever for movement from each of its extreme positions to the other but which when deenergized prevents such movement of said lever, an auxiliary circuit controller having a first and a second position, a second manually controllable traffic device having a first and a second position associated with the opposite end of said stretch, a second auxiliary circuit controller biased toward a first position but manually operable to a second position, a stick relay, a pick-up circuit for said stick relay controlled by said second auxiliary circuit controller in its second position, a stick circuit for said stick relay controlled by said traffic lever in the normal position, an indication device, means controlled by a front contact of said stick relay and by said first auxiliary circuit controller 35

in said first position for energizing said lock and said indication device, a second indication device, means controlled by said traffic lever in the normal position and by said second traffic device in its first position for energizing said second indication device, a third indication device, means controlled by said traffic lever in the reverse position and by said second traffic device in its second position for energizing said third indication device and for energizing means for directing traffic movements over said stretch in a second or opposite direction, and means controlled by said first auxiliary circuit controller in its second position and by a back contact of said stick relay and also by said traffic lever in its reverse position and by said second traffic device in its second position for deenergizing said third indication device.

4. In combination, a stretch of railway track, 20 a manually controllable traffic lever associated with one end of said stretch having a normal position for governing traffic movements in a first given direction over said stretch and also having a reverse position, a lock for said lever which when energized releases said lever for movement from each of its extreme positions to the other but which when deenergized prevents such movement of said lever, a second manually controllable traffic device operable at any time 25 to a first and a second position associated with the opposite end of said stretch, a first and a second manually operable auxiliary circuit controller associated with said traffic lever and said second traffic device respectively, means controlled by 30 operation of said second auxiliary circuit controller for effecting energization of said lock to permit movement of said traffic lever to the reverse position, means controlled by said traffic lever in its reverse position and by said second traffic device 35 in its second position for directing traffic movements in a second or opposite direction over said stretch, and means controlled by operation of said first auxiliary circuit controller and by operation of said traffic lever to its reverse position 40 and also by operation of said second traffic device to its second position followed by operation of said second traffic device to its first position for effecting energization of said lock to permit movement of said traffic lever to the normal 45 position.

5. In combination, a stretch of railway track, 50 a manually controllable traffic lever associated with one end of said stretch having a normal position for governing traffic movements in a first given direction over said stretch and also having a reverse position, a lock for said lever which when energized releases said lever for movement from each of its extreme positions to the other but which when deenergized prevents such movement of said lever, a second manually controllable traffic device operable at all times to 55 a first and a second position associated with the opposite end of said stretch, a first and a second manually operable auxiliary circuit controller associated with said traffic lever and said second traffic device respectively, an indication device, means controlled by operation of said second auxiliary circuit controller for effecting energization of said indication device and for effecting energization of said lock to permit movement of said traffic lever to the reverse position, means controlled by said traffic lever in its reverse position and by said second traffic device in its second position for directing traffic movements in the opposite direction over said stretch, a second and a 60

third indication device, means controlled by said traffic lever in the normal position and by said second traffic device in its first position for energizing said second indication device, means controlled by said traffic lever in the reverse position and by said second traffic device in its second position for energizing said third indication device, means controlled by operation of said first auxiliary circuit controller while said traffic lever is in its reverse position and while said second traffic device is in its second position for deenergizing said third indication device, and means controlled by the subsequent return of said second traffic device to its first position for effecting energization of said lock to permit movement of said traffic lever to its normal position. 5

6. In combination, a stretch of railway track, a manually controllable traffic lever associated with one end of said stretch having a normal position for governing traffic movements in a first given direction over said stretch and also having a reverse position, a lock for said lever which when energized releases said lever for movement from each of its extreme positions to the other but which when deenergized prevents such movement of said lever, a second manually controllable traffic device operable at all times to a first and a second position associated with the opposite end of said stretch, a first and a second manually operable auxiliary circuit controller associated with said traffic lever and said second traffic device respectively, means controlled by operation of said second auxiliary circuit controller for effecting energization of said lock to permit movement of said traffic lever to the reverse position, means controlled by said traffic lever in its reverse position and by said second traffic device in its second position for directing traffic movements in the opposite direction on said stretch, a stick relay, a pick-up circuit for said stick relay controlled by operation of said first auxiliary circuit controller while said second traffic device is in its second position, a stick circuit for said stick relay controlled by said traffic lever in its reverse position, and means controlled by said stick relay in its energized condition and by said second traffic device in its first position for effecting energization of said lock to permit movement of said traffic lever to the normal position. 20 25 30 35 40 45 50

7. In combination, a stretch of railway track, a manually controllable traffic lever associated with one end of said stretch having a normal position for governing traffic movements in a first given direction over said stretch and also having a reverse position, a lock for said lever which when energized releases said lever for movement from each of its extreme positions to the other but which when deenergized prevents such movement of said lever, a second manually controllable traffic device operable at all times to a first and a second position associated with the opposite end of said stretch, a first and a second manually operable auxiliary circuit controller associated with said traffic lever and said second traffic device respectively, a stick relay, a pick-up circuit for said stick relay controlled by operation of said second auxiliary circuit controller, a stick circuit for said stick relay controlled by said traffic lever in the normal position, means controlled by a front contact of said stick relay for energizing said lock to permit movement of said traffic lever to the normal or the reverse position, means controlled by said traffic lever in the reverse position and by said second traffic device in 70 75

- its second position for governing traffic movements in the opposite direction on said stretch, and a second pick-up circuit for said stick relay controlled by operation of said first auxiliary circuit controller and by operation of said traffic lever to its reverse position and also by operation of said second traffic device to its second position followed by operation of said second traffic device to its first position.
5. 8. In combination, a stretch of railway track, a manually controllable traffic lever associated with one end of said stretch having a normal position for governing traffic movements in a first given direction over said stretch and also having a reverse position, a lock for said lever which when energized releases said lever for movement from each of its extreme positions to the other but which when deenergized prevents such movement of said lever, a second manually controllable traffic device operable at all times to a first and a second position associated with the opposite end of said stretch, a first and a second manually operable auxiliary circuit controller associated with said traffic lever and said second traffic device respectively, a stick relay, a reverse traffic stick relay, means controlled by operation of said second auxiliary circuit controller and by a front contact of said normal stick relay for effecting energization of said lock, means controlled by said traffic lever in its reverse position and by said second traffic device in its second position for governing traffic movements in the opposite direction on said stretch, a stick traffic control relay, a pick-up circuit for said stick traffic control relay controlled by operation of said first auxiliary circuit controller and by a front contact of said reverse traffic stick relay, a stick circuit for said stick traffic control relay controlled by said traffic lever in its reverse position, a pick-up circuit for said normal traffic stick relay controlled by said second traffic device in its first position and also controlled by a front contact of said stick traffic control relay in multiple with a contact closed by said traffic lever in its normal position, a pick-up circuit for said reverse traffic stick relay controlled by said traffic lever in its reverse position and by said second traffic device in its second position, a stick circuit for each of said normal and reverse traffic stick relays controlled by a back contact of the other, a second stick circuit for said normal traffic stick relay controlled by said traffic lever in the normal position, a second stick circuit for said reverse traffic stick relay controlled by a train on said stretch, and other means controlled by front contacts of said normal traffic stick relay and said stick traffic control relay for effecting energization of said lock.
9. In combination, a stretch of railway track, a manually controllable traffic lever associated with one end of said stretch having a normal position for governing traffic movements in a first given direction over said stretch and also having a reverse position, a second manually controllable traffic device having a first and a second position associated with the opposite end of said stretch, a first and a second manually operable auxiliary circuit controller associated with said traffic lever and said second traffic device respectively, an indication device, means controlled by operation of said second auxiliary circuit controller and by said traffic lever in the normal position for energizing said indication device, means controlled by said traffic lever in its reverse position and by said second traffic device in its second position for governing traffic movements in the opposite direction on said stretch, a second and a third indication device, means controlled by said traffic lever in the normal position and by said second traffic device in its first position for energizing said second indication device, means controlled by said traffic lever in the reverse position and by said second traffic device in its second position for energizing said third indication device, and means controlled by operation of said first auxiliary circuit controller and by said traffic
- lever in the reverse position and also by said second traffic device in its second position for de-energizing said third indication device.
10. In combination, a stretch of railway track, a manually controllable traffic lever associated with one end of said stretch having a normal position for governing traffic movements in a first given direction over said stretch and also having a reverse position, a lock for said lever which when energized releases said lever for movement from each of its extreme positions to the other but which when deenergized prevents such movement of said lever, a second manually controllable traffic device operable at all times to a first and a second position associated with the opposite end of said stretch, a first and a second manually operable auxiliary circuit controller associated with said traffic lever and said second traffic device respectively, a normal traffic stick relay, a reverse traffic stick relay, means controlled by operation of said second auxiliary circuit controller and by a front contact of said normal stick relay for effecting energization of said lock, means controlled by said traffic lever in its reverse position and by said second traffic device in its second position for governing traffic movements in the opposite direction on said stretch, a stick traffic control relay, a pick-up circuit for said stick traffic control relay controlled by operation of said first auxiliary circuit controller and by a front contact of said reverse traffic stick relay, a stick circuit for said stick traffic control relay controlled by said traffic lever in its reverse position, a pick-up circuit for said normal traffic stick relay controlled by said second traffic device in its first position and also controlled by a front contact of said stick traffic control relay in multiple with a contact closed by said traffic lever in its normal position, a pick-up circuit for said reverse traffic stick relay controlled by said traffic lever in its reverse position and by said second traffic device in its second position, a stick circuit for each of said normal and reverse traffic stick relays controlled by a back contact of the other, a second stick circuit for said normal traffic stick relay controlled by said traffic lever in the normal position, a second stick circuit for said reverse traffic stick relay controlled by a train on said stretch, and other means controlled by front contacts of said normal traffic stick relay and said stick traffic control relay for effecting energization of said lock.
11. In combination, a stretch of railway track, a manually movable traffic control lever associated with a first end of said stretch having a normal and a reverse extreme position and also having a reverse lock position between said extreme positions, a lock for said lever which when deenergized prevents movement of said lever past said reverse lock position toward said normal position but which when energized releases said lever, an auxiliary circuit controller having a first and a second control position, a second manually operable traffic control device having a normal and a reverse position associated with the opposite end of said stretch, an auxiliary traffic control relay, a circuit controlled by said traffic control lever in the reverse position and by said auxiliary circuit controller in its second position and also by operation of said second traffic control device to its reverse position for energizing said auxiliary traffic control relay, a second circuit controlled by said traffic control lever in the reverse lock position and by said auxiliary circuit controller in its first position and by

operation of said second traffic device to its normal position and also by said auxiliary traffic control relay first in the energized condition and then in the deenergized condition for effecting 5 energization of said lock, and means controlled by said traffic control lever and by said second traffic control device in the normal and reverse positions for directing traffic movements in a first direction and in the opposite direction respectively over said stretch. 10

12. In combination, a stretch of railway track, a manually controllable traffic control device associated with a first end of said stretch having a normal and a reverse position, an auxiliary circuit controller biased toward a first position but manually operable to a second position, a second manually controllable traffic control device having a normal and a reverse position associated with the opposite end of said stretch, a stick traffic control relay, an indication device, a pick-up circuit for said stick traffic control relay controlled by said auxiliary circuit controller in its second position and by said second traffic control device in its reverse position, a 15 stick circuit for said stick traffic control relay controlled by said first manually controllable traffic control device in its reverse position, means controlled by said first and second manually controllable traffic control devices both in the reverse 20 position for energizing said indication device, means controlled by a front contact of said stick traffic control relay for deenergizing said in- 25

30

30 dication device, and means controlled by said first and second traffic control devices in the normal and reverse positions for governing traffic movements in both directions over said stretch.

13. In combination, a stretch of railway track, 5 a manually controllable traffic lever associated with one end of said stretch having a normal position for governing traffic movements in a first given direction over said stretch and also having a reverse position, a lock for said lever which 10 when deenergized prevents movement of said lever from the reverse to the normal position but which when energized releases said lever for such movement, a second manually controllable traffic device operable at any time to a first and 15 a second position associated with the opposite end of said stretch, a manually operable auxiliary circuit controller associated with said traffic lever, means controlled by said traffic lever in its reverse position and by said second traffic device in its second position for directing traffic movements in a second or opposite direction over 20 said stretch, and means controlled by operation of said auxiliary circuit controller and by operation of said traffic lever to its reverse position 25 and also by operation of said second traffic device to its second position followed by operation of said second traffic device to its first position for energizing said lock to permit movement of said traffic lever to the normal position. 30

JAMES J. VANHORN.
